(57) **CLAIM**

The ornamental design for a light fixture, as shown and described.

DESCRIPTION

This application is related to commonly assigned U.S. applications Ser. No. 29/216,036, Ser. No. 29/215,997, Ser. No. 29/216,074, and Ser. No. 29/216,073 and concurrently filed application No. 29/221,164 the full disclosure of these applications being incorporated herein by reference.

FIG. 1 is an isometric view of a first embodiment of the light fixture of the present invention;

FIG. 2 is a front elevation view thereof, the right side elevation view being a mirror image thereof;

FIG. 3 is a top plan elevation view thereof;

FIG. 4 is a bottom plan elevation view thereof; and,

FIG. 5 is an isometric view of a second embodiment.

The broken line showing is for illustrative purposes only and forms no part of the claimed invention.
